Application August 22, 1939, Serial No. 291,386

19 Claims. (Cl. 246—34)

Our invention relates to railway traffic controlling apparatus and more particularly to apparatus for preventing false energization of the track relay due to foreign current which may be induced in the rails of the track from propulsion conductors or other power conductors carrying heavy alternating current in proximity to the rails of the track.

We shall describe two forms of apparatus embodying our invention, and shall then point out the novel features thereof in claims.

In the accompanying drawing, Fig. 1 is a diagrammatic view showing one form of apparatus embodying our invention as applied to a simple type of non-coded, electric road track circuit. Fig. 2 is a diagrammatic view showing a modified form of the apparatus of Fig. 1, also embodying our invention, as applied to a coded electric road track circuit adapted for controlling train movements in either direction.

Similar reference characters refer to similar parts in each of the two views.

In electrified territory where alternating current is used as the propulsion energy, it is necessary for reasons of safety to employ alternating current of a different frequency for energizing the track circuits which control the essential signaling apparatus on which safety of train movement depends. The frequency separation between the propulsion and track circuit currents is ordinarily such as will insure that the track circuit apparatus will not operate falsely at the maximum values of propulsion current to which such apparatus may be subjected in service. For example, where the propulsion current frequency is 25 cycles, then 60 cycle or 100 cycle signaling current may be used. Immunity is obtained by using a frequency selective track relay such, for example, as a centrifugal frequency relay or a vane frequency relay. These relays are well known and it will be sufficient to say that the centrifugal relay employs a rotating, inertia element of the fly-ball governor type so designed as to be incapable of closing certain contacts at the relatively low speed which the rotating element attains when energized by current of the propulsion frequency.

If the propulsion current which reaches the track relay is substantially sinusoidal, no appreciable danger of false operation is present. Instances may occur, however, where the propulsion current contains prominent harmonics and since the amount of track circuit current necessary for operating a track relay must necessarily be rather small for reasons of sensitive track circuit

shunting protection, sufficient harmonic current may at times be present to produce false operation of the track relay. Although it is the aim to cause the propulsion current to divide equally between the two rails of a track section in a multiple track road, nevertheless, because of unavoidable differences in the bonding, self and mutual inductance effects, and many other factors, a considerable unbalance in the propulsion current as between the two rails of a track circuit is frequently met with in practice. Moreover, in the event of a broken rail and a train occupying the section, the control element of a track relay may acquire a substantial propulsion potential while at the same time, the local element may also receive an even higher propulsion potential from the signal transmission line upon which the track propulsion voltage has been impressed in the step-up direction through the track transformer. In this manner, false operation of the track relay may result. Also, a similar undesired effect may be produced if sufficient induction in the rails from power lines which parallel the track section is present. For these reasons, some means not dependent on frequency separation alone is essential for insuring safety of track circuit operation on alternating current propulsion roads. Our invention enables this protection to be obtained in a simple and reliable manner.

Referring to Fig. 1, the reference characters 1 and 1a designate the track rails of a stretch of alternating current propulsion railway which rails are divided by insulated joints 2 to form a track section A—B. Impedance bonds 1B are connected across the rails of the track at locations A and B to provide a path for the flow of propulsion current around the insulated joints 2, in the usual manner. Located at one end of the section A—B is a suitable frequency selective two-element alternating current track relay TR having the usual control winding 3 connected across the rails of the track, and also having a local winding 4. This local winding is energized from a source of alternating current of which only the terminals BX—CX are shown. The frequency of this source is, of course, substantially different from that which supplies the propulsion current. Both windings 3 and 4 must be simultaneously energized before relay TR will pick up. Located at the other end of the section is a track transformer T having a primary winding 8 and a secondary winding 9. The latter winding furnishes operating current for the control element of relay TR through the current limiting device 55

R which may be either a resistor or a reactor as determined by phase displacement considerations.

In order to prevent false energization of relay 5 TR, we have provided a two-element alternating current checking relay CR. As shown, one element 5 of this checking relay is connected across the primary winding 8 of transformer T, whereas the other element 6 of this relay is connected 10 in series with this same transformer winding. It will be apparent, however, from the description which follows that if desired, the element 5 may be connected in multiple across winding 9 or across the terminals BX-CX of the source, and 15 that the element 6 may be connected in series with winding 9 between the rails and the track transformer, with like effect. It is not necessary that the element 6 be included directly in the series circuit with a winding of the track transformer as, obviously, a suitable transformer may 20 be interposed in order to obtain the desired operating potential across the element 6. The relay CR, like the track relay, is so designed that it will pick up only when the two elements 5 and 25 6 are simultaneously energized with current from the same source and only if the proper relative instantaneous polarity exists between these two elements. For maximum protection, relay CR may also be of the frequency selective type, such 30 as the track relay TR. As long as relay CR remains energized and maintains its front contact 35 7 closed during the time that the track section A-B is unoccupied, the track relay TR will remain picked up because its local winding 4 will receive energy over the front contact 7 and its 40 control winding 3 will receive energy from the track in the usual manner. Should relay CR become released for any reason, front contact 7 will open, thus causing relay TR immediately to release.

We shall now describe the way in which relay CR provides foreign current protection to the track relay. It will be noted that with the transformer T properly energized from the source BX-CX through the fuse F and winding 6 of relay CR, then at a given instant, the instantaneous relative polarity of the terminals of transformer winding 8 and of the relay winding 5 with 45 respect to the other relay winding 6 will be as indicated on the drawing. Under this condition, pick-up torque will be developed in the relay CR so that front contact 7 will be maintained closed and will cause winding 4 of relay TR to be maintained energized. Also, the current supplied to 50 winding 3 of the track relay TR over the track circuit will be of the proper polarity for developing normal torque in this relay. Assuming, however, that an appreciable amount of foreign current is induced in the rails 1 and 1a from an adjacent 55 propulsion conductor or that unbalanced propulsion current containing prominent harmonics flows in the track transformer T, this current will cause winding 9 of the track transformer to act as a primary, inducing current of the 60 propulsion frequency in winding 8 of the transformer and stepping up the voltage of this current due to the usual transformer ratio. If we assume that at some given instant the instantaneous polarity of winding 8 due to the foreign current induced therein is that which is indicated 65 on the drawing, then it will be readily apparent that the instantaneous relative polarity of winding 6 due to the flow of the foreign current will become reversed from that which is shown on the 70 drawing. Therefore, although the instantaneous 75

relative polarity of winding 5 of the relay CR due to the foreign current may be that shown on the drawing, the other winding 6 of this relay will have its instantaneous polarity reversed, so that the torque developed in relay CR due to the foreign current will be in the reverse direction and will cause front contact 7 to open and to release the track relay TR in the event that the foreign current reaches a dangerous value.

A particularly dangerous condition which 10 might arise on track circuits in which protection such as herein disclosed is not provided, is that occasioned by broken wires or blown fuses at certain points in the signaling current supply circuit such that the only load connected in 15 multiple with the input terminals of a given track transformer is the local element 4 of the track relay. Under this condition, the voltage induced in winding 8 by foreign current harmonics and stepped up through the track transformer would 20 be particularly effective in aiding false operation of the track relay because of the absence of additional load which would ordinarily tend to decrease the effectiveness of the foreign current. However, when a checking relay such as CR is 25 used, a heavy foreign current will cause a correspondingly strong reverse torque to be developed in this relay, thus reducing the possibility of false pick-up of the track relay.

It will be apparent from the foregoing that the 30 circuit connections of the checking relay are such that as long as the flow of track circuit power is in the direction from the signaling source or transmission line to the track, this relay will remain energized, but when the direction of the 35 flow of power is reversed, that is, when foreign current energy is being fed from the track to the transmission line, the relative instantaneous polarity of windings 5 and 6 with respect to such foreign current will reverse, thus producing a 40 reverse torque in the checking relay which will cause this relay to release when the amount of the foreign current reaches a dangerous value. It will be understood, of course, that the development of a reverse torque in the checking relay 45 does not necessarily depend on the presence of offending harmonics in the propulsion current or on a particular frequency of the foreign current, but merely on the direction in which power is being transferred between the track rails and 50 the source BX-CX.

Referring now to Fig. 2, this figure shows the checking relay of Fig. 1 applied to a coded train control track circuit over which traffic may move in either direction. The track relay TRA is controlled as in Fig. 1 over a front contact 7 of the checking relay CRA which causes the local winding 4 to become deenergized whenever a dangerous amount of foreign current is present in the track transformer TA. The westbound traffic 60 direction relay DRW controls the application of train control code to the track circuit by means of transformer TB at location C for controlling westbound traffic. Similarly, the eastbound traffic direction relay DRE controls the application 65 of train control code to the track circuit by means of the transformer TA at location D, thereby controlling eastbound traffic. Relay DRE also at times controls over its front contact 12, the effective impedance of the transformer AT in the 70 track relay circuit for a purpose to be described hereinafter. The control circuits for relays DRW and DRE are well known and since these circuits are unnecessary for an understanding of our invention, a description thereof will not be given 75

other than to state that when eastbound traffic approaches the section C—D from the left, relay DRE will be picked up and relay DRW will be released, whereas when westbound traffic approaches the section from the right, relay DRW will be picked up and relay DRE will then be released.

Relay AR is an approach control relay which is effective whenever the section C—D becomes occupied, for starting the operation of the code transmitter CT and for closing certain other circuits to be described hereinafter. The checking relay CRA is a code following relay which controls the local winding 4 of relay TRA, as before, and which in addition, controls the impedance of the auxiliary transformer AT over its contact 13 in order to permit relay TRA to pick up following the exit of a westbound train from the section.

Having described the individual apparatus shown in Fig. 2, we shall next describe the operation of this apparatus when a train passes over the section.

Normally, when no train is in the section, the control element 3 of the track relay is steadily energized from the rails by virtue of the fact that the track transformer TA is steadily energized over a circuit which extends from one terminal BX of a suitable alternating current source, through front contact 14—15 of the normally energized approach relay AR, wire 16, front contact 17—18 of relay DRE (assuming that a route has been established for eastbound traffic), wire 19, winding 6 of relay CRA, wire 20, and winding 8 of track transformer TA, to the other terminal CX of the source. The impedance of winding 10 of transformer AT will be low because the other winding 11 of this transformer will be short-circuited over the multiple connected contacts 12, 13, and 23 of relays DRE, CRA, and AR, respectively. The local element 4 of relay TRA will also be steadily energized over a circuit which may be traced from one terminal BX, through front contact 14—15 of relay AR, wires 16 and 21, front contact 7 of relay CRA, wire 22, and winding 4, to the other terminal CX of the source. Accordingly, relay TRA will remain picked up under this condition. Relay CRA will also be picked up because its element 6 will be steadily energized over the circuit previously traced for transformer TA, and its element 5 will be steadily energized over an obvious circuit which includes front contact 14—15 of relay AR.

When an eastbound train enters the section C—D, relay TRA will release, opening the circuit for the approach relay at front contact 24. The release of relay AR will close back contact 25, starting the operation of the code transmitter CT, and will also establish a coding connection for wire 16 over back contact 15—26. It will be understood that the code transmitter CT may be any suitable type of motor operated contactor or reciprocating armature device which periodically and alternately closes the contacts 28—29 and 28—31. Code will now be supplied to the track transformer TA and to the track rails ahead of the train over the same circuit previously traced for transformer TA except now extending from terminal BX, through the usual code selection circuits which are well known and are therefore not shown, for simplicity, wire 27, contact 28—29 of the code transmitter CT, wire 30 and back contact 15—26 of relay AR, to wire 16 and the remainder of the circuit for transformer TA, previously traced. Relay CRA will receive

code in both of its elements 5 and 6 over obvious circuits, and since this relay is designed to follow code, it will intermittently open and close its contacts 7 and 13. No function is served by the periodic opening of these contacts under the eastbound traffic conditions except that this operation provides a check on the mechanical integrity of the checking relay.

When the train leaves the section, the removal of the train shunt will cause coded energy to flow in winding 3 of the track relay, the impedance of winding 10 being maintained at its low value due to the steadily closed contact 12 of relay DRE and the periodically closed contact 13 of relay CRA. Coded energy will also simultaneously flow in winding 4 of the track relay due to the periodic closing of contact 7 so that relay TRA will pick up and in so doing will energize relay AR to de-energize the code transmitter CT and to restore steady energy to the apparatus over the front contact 14—15, thus restoring the apparatus to the condition in which it is shown in the drawing.

Assuming next that a westbound route has been established so that relay DRW is energized and relay DRE is deenergized, if a train now enters the track section from the right, the track relay TRA will again become deenergized and will release relay AR. Relay AR will start the operation of the code transmitter, as before, but the energy received by the track circuit will under this condition be a combination of code supplied from the transformer TB for train control purposes and of steady energy from the transformer TA for the purpose of enabling the track relay to pick up after the train clears the section.

The circuit for energizing transformer TB may be traced from terminal BX, through the code selection circuits, wire 21, contact 28—31 of code transmitter CT, wire 32, front contact 33 of relay DRW, wire 34, back contact 35 of relay AR, wire 36, and the input winding of transformer TB, to the other terminal CX of the source. The coded output from the transformer TB is impressed across the rails through a suitable current limiting reactor X. This coded output is not effectively shunted by the track relay winding 3 because of the substantial impedance simultaneously introduced by winding 10 at code intervals when winding 11 is open circuited. The latter winding will be on open circuit at code intervals because contact 13 will open each time that contact 28—29 of the code transmitter CT becomes open during the code cycle. Thus, the code following operation of relay CRA provides a recurrent check showing whether the train has or has not left the section. Element 6 of relay CRA will be steadily energized over back contact 18—37 of relay DRE, but since element 5 will receive coded energy, relay CRA will follow code.

When the train leaves the section, the train shunt will be removed from relay TRA and this relay will begin to receive pick-up energy as soon as a succeeding code impulse closes front contact 13 of relay CRA and causes the impedance of winding 10 to drop to its low value. Winding 4 will, of course, receive energy simultaneously with winding 3 so that relay TRA will pick up on code and having picked up, will restore relay AR and code transmitter CT to their original condition. The opening of contact 35 of relay AR will disconnect energy from the transformer TB, irrespective of whether relay DRW is or is not restored to its deenergized condition. Steady energy will now be restored to the track circuit and

to relay CRA over front contact 14-15 so that this apparatus will again be restored to the condition in which it is illustrated.

If at any time when the section is either oc-

- 5 cupied or unoccupied, a dangerous amount of propulsion energy or other foreign current should appear in the winding 8 of the track transformer, the instantaneous relative polarity of winding 6 due to such current will be immediately reversed 10 10 with respect to winding 5 so that a reverse torque will be developed in relay CRA which will cause this relay to become effectively released, thus eliminating the possibility of false operation of 15 the track relay and the display of a less restrictive indication than that warranted by traffic conditions.

Although we have herein shown and described only two forms of railway traffic controlling apparatus embodying our invention, it is understood 20 20 that various changes and modifications may be made therein within the scope of the appended claims without departing from the spirit and scope of our invention.

Having thus described our invention, what we 25 claim is:

1. In combination with a section of railway track, a two-element alternating current track relay having one element connected so as to receive energy from the rails of said section, a 30 30 source of alternating current, a track transformer having its input winding energized from said source and having its output winding supplying energy to said one element of the track relay over the rails of said section, a two-element alternating current checking relay having one element energized from said source and having the other element energized from a series connection between said source and said transformer input winding, and means governed by said checking 35 35 relay for controlling the energization of the other element of said track relay from said source to thereby maintain said track relay normally energized, whereby in the event of sufficient foreign current energy passing from said output to said 40 40 input winding of the track transformer, the torque in said checking relay will reverse to cause said checking relay to release and so to cause said track relay to assume its deenergized position.

- 50 2. In combination with a section of railway track, a source of periodic current, a track transformer having its input winding energized from said source and supplying energy from its output winding to the rails of said section, a two-element 55 55 track relay having one element connected so as to receive energy from said source over the rails of said section, a two-element checking relay having one element energized from across a winding of said track transformer and having the other element energized from a series connection with a winding of said track transformer, and means governed by said checking relay for controlling the supply of current from said source to the other element of said track relay.

- 60 3. In combination with a section of railway track, a source of periodic current, a track transformer having its input winding connected with said source and having its output winding connected across the rails of said section, a two- 65 70 element track relay having one element connected across the rails of said track, a two-element checking relay having one element connected across a winding of said track transformer and having the other element energized over a series connection with a winding of said track trans-

former, and means including a contact of said checking relay for controlling the supply of current from said source to the other element of said track relay.

4. In combination with a section of railway track, a source of periodic current, a track transformer having its input winding connected with said source and having its output winding connected across the rails of said section, a two-element track relay having one element connected across the rails of said track, a two-element checking relay having one element energized from said source and having the other element included in series between said source and a winding of said track transformer, and means governed by said checking relay for controlling the supply of current from said source to the other element of said track relay to thereby maintain said track relay normally energized, whereby foreign current energy flowing from the rails into 20 said track transformer causes the instantaneous relative polarity of one element of said checking relay to reverse, thereby causing the control function of said checking relay to become exercised if a dangerous amount of said foreign current flows in said track transformer.

5. In combination with a section of railway track, a source of periodic current, a track transformer having its input winding connected with said source and having its output winding connected across the rails of said section, a two-element track relay having one element connected across the rails of said track, a two-element checking relay having one element energized from said source and having the other element included in series with a winding of said track transformer, and means including a contact of said checking relay for controlling the supply of current from said source to the other element of said track relay to thereby maintain said track relay normally energized, whereby foreign current energy flowing from the rails into said track transformer causes the instantaneous relative polarity of one element of said checking relay to reverse, thereby causing the control function of said checking relay to become exercised if a dangerous amount of said foreign current flows in said track transformer.

6. In combination with a section of railway track, a source of periodic current, a track transformer having its input winding connected with said source and having its output winding connected across the rails of said section, a two-element track relay having one element connected across the rails of said track, a two-element checking relay having one element energized from said source over a multiple connection with a winding of said track transformer and having the other element energized from said source over a series connection with a winding of said track transformer, and means governed by said checking relay for controlling the supply of current from said source to the other element of said track relay to thereby maintain said track relay normally energized, whereby if a dangerous amount of foreign current energy flows from the rails into said track transformer, said checking relay will operate to cause said track relay to release.

7. In combination with a section of railway track, a source of periodic current, a track transformer having its input winding connected with said source and having its output winding connected across the rails of said section, a two-element track relay having one element con-

5 nected across the rails of said section, a normally ineffective impedance included in the connection of said one element with one of said rails, a two-element checking relay having one element energized from said source over a multiple connection with a winding of said track transformer and having the other element energized from said source over a series connection with a winding of said track transformer, means governed 10 by said checking relay for controlling the supply of current from said source to the other element of said track relay, and other means governed by said checking relay effective when said section is occupied by a train entering from a 15 given direction for rendering said impedance periodically ineffective to thereby enable said track relay to become energized after said train leaves the section, whereby if a dangerous amount of foreign current energy flows from the rails into 20 said track transformer, said checking relay will operate to deprive said other element of the track relay of energy, thereby insuring a release of said track relay.

25 8. In combination with a section of railway track over which traffic may move in either direction, a source of periodic current, a track transformer having its input winding connected with said source and having its output winding connected across the rails at one end of said section, a two-element track relay energized from said source and having one element connected across the rails at the other end of said section in series with an impedance, a traffic direction 30 relay for each direction of traffic over said section, a two-element code following checking relay having one element energized from said source over a multiple connection with a winding of said track transformer and having the other element energized from said source over a 35 series connection with a winding of said track transformer, means including a front contact of one of said traffic direction relays in multiple with a front contact of said checking relay for rendering said impedance ineffective, a front 40 contact of said one traffic direction relay included in the energizing circuit for said other element of the checking relay, said last named contact being included in the connection of said track transformer with said source, means including a front contact of said checking relay for supplying current from said source to the other element of said track relay, means including a back contact of said one traffic direction 45 relay for supplying current from said source to said track transformer and said other element of the checking relay, means including a front contact of the other of said traffic direction relays effective when said section is occupied for supplying coded train control current across the 50 rails at said other end of the section, and means also effective when said section is occupied for supplying coded current from said source alternately with said coded train control current to said one element of said checking relay to thereby cause said checking relay to follow code, 55 whereby said impedance will be rendered ineffective at code intervals to enable said track relay to pick up following the exit of a train from said section.

9. In combination with a section of railway track over which traffic may move in either direction, a source of periodic current, a track transformer energized from said source and having its output winding connected across the rails at one end of said section, a two-element track relay having one element connected across the rails at the other end of said section, a two-element code following checking relay, a traffic direction relay, a code transmitter, means effective when said section is unoccupied for supplying uncoded current from said source to one element of said checking relay, means effective when said section is unoccupied and said traffic direction relay is either energized or deenergized for supplying uncoded current from said source to the other element of said checking relay and to said track transformer in series, means effective when said section is occupied and said traffic direction relay is energized for supplying coded current to both elements of said checking relay and to said track transformer whereby said checking relay will follow code, means controlled by a front contact of said checking relay for energizing the other element 25 of said track relay at code intervals whereby said track relay will pick up when the section becomes unoccupied, and means effective when said track relay picks up for discontinuing the operation of said code transmitter. 30

10. In combination with a section of railway track over which traffic may move in either direction, a source of periodic current, a track transformer energized from said source and having its output winding connected across the rails 35 at one end of said section, a two-element track relay having one element connected across the rails at the other end of said section in series with an impedance, a two-element code following checking relay, a traffic direction relay, a code 40 transmitter having a normal and a reverse contact, means effective when said section is unoccupied for supplying uncoded current from said source to one element of said checking relay as well as to the other element of said checking 45 relay and said track transformer in series, means effective when said section is occupied for initiating operation of said code transmitter, means effective when said section is occupied and said traffic direction relay is energized for supplying 50 train control code to the rails at said other end of the section over said reverse contact of the code transmitter, means effective when said section is occupied for supplying coded current to said one element of the checking relay over said 55 normal contact of the code transmitter whereby said checking relay will follow code, means controlled by a front contact of said checking relay for rendering said impedance ineffective at code intervals, means also controlled by a front contact of said checking relay for energizing the other element of said track relay at code intervals whereby said track relay will pick up when the section becomes unoccupied, and means effective when said track relay picks up for discontinuing the operation of said code transmitter. 60 65
